CLAIM

The ornamental design for a dispenser housing, as shown and described.

DESCRIPTION

FIG. 1 is an isometric view of a top, front, and left side of an ornamental design for a dispenser housing;
FIG. 2 is a front elevational view of the dispenser housing of FIG. 1;
FIG. 3 is a rear elevational view of the dispenser housing of FIG. 1;
FIG. 4 is a right side elevational view of the dispenser housing of FIG. 1;
FIG. 5 is a left side elevational view of the dispenser housing of FIG. 1;
FIG. 6 is a top plan view of the dispenser housing of FIG. 1;
FIG. 7 is a bottom plan view of the dispenser housing of FIG. 1;
FIG. 8 is an isometric view of a top, front, and left side of a different embodiment of an ornamental design for a dispenser housing;
FIG. 9 is a front elevational view of the dispenser housing of FIG. 8, all other sides being identical thereto;
FIG. 10 is a top plan view of the dispenser housing of FIG. 8;
FIG. 11 is a bottom plan view of the dispenser housing of FIG. 8;

FIG. 12 is an isometric view of a top, front, and left side of a further embodiment of an ornamental design for a dispenser housing;
FIG. 13 is a front elevational view of the dispenser housing of FIG. 12, all other sides being identical thereto;
FIG. 14 is a top plan view of the dispenser housing of FIG. 12; and,
FIG. 15 is a bottom plan view of the dispenser housing of FIG. 12.

The broken lines are for the purpose of illustrating environmental structure and form no part of the claimed design.
